DIAPHRAGM VESTIBULE CONSTRUCTION FOR RAILWAY CARS

Harry L. Decker, Altoona, Pa., assignor to The Pennsylvania Railroad Company, Philadelphia, Pa., a corporation of Pennsylvania

Application January 5, 1934, Serial No. 705,392

12 Claims. (Cl. 105—15)

This invention relates to diaphragm vestibules such as are commonly used on railway cars to form closed connecting passages between contiguous units of a train.

5 In car vestibules as ordinarily constructed, the
face plates to which the outer edges of the col-
lapsible diaphragms are secured, are supported
by rearwardly extending buffer stems confined
to longitudinal movement in fixed guides on the
10 car bodies. By reason of this arrangement, the
abutting faces of the diaphragm plates of the
contiguous vestibules are incapable of adapt-
ing themselves mutually to compensate for dif-
ferential or contrary swaying and pitching of
15 the car ends in normal straight-away travel or
for angular deviations of the cars incident to
rounding of track curves. Accordingly, under
such conditions, the diaphragm face plates rub
against each other, producing disagreeable grat-
ing noises, in addition to rattling caused by
20 looseness of the parts and through binding and
straining action of the buffer stems in their
guides.

25 My invention is directed in the main toward overcoming the aforementioned drawbacks, that is to say: it has for its chief aim the provision of a car vestibule structure wherein the dia-
phragm face plate is supported with capacity for yielding to universal movement so that abutting
30 vestibule diaphragms of contiguous cars of a train can adapt themselves compensatively to each other with consequent avoidance of relative movement between them and the elimination of objectionable grating noises incident to train
35 operation.

39 In connection with a vestibule structure having the above attributes, I also aim to provide for the absorption of looseness between the constituent parts with a view toward further minimization of the noises.

40 Still other objects and advantages of this in-
vention will be manifest from the detailed de-
scription following of the attached drawings,
wherein Fig. I is a fragmentary view, partly in
45 side elevation and partly in longitudinal sec-
tion, of a railway car conveniently embodying
my improved diaphragm vestibule construction.

Fig. II shows the vestibule in end elevation, or as viewed from the left of Fig. I, with a portion thereof broken away to expose important details which would otherwise be concealed.

With more detailed reference to these illustrations, the numeral 5 comprehensively designates the diaphragm vestibule, whereof the diaphragm 6 has its inner edge secured directly to

the car end 7 and its outer end to the diaphragm face plate 8 in the customary manner.

In accordance with my invention, the diaphragm face plate 8 is supported in suspension by a pair of hanger rods 9 disposed along opposite sides thereof and inclined somewhat to the vertical when viewed from the side of the car as shown in Fig. I. The lower ends of the hanger rods 9, it will be observed, are respectively connected by pivot pins 10 to bracket pieces 11 at 10 opposite ends of the lower cross member or buffer plate portion 12 of the diaphragm plate. The upper ends of the hanger rods 9 slidingly engage apertured brackets 13 riveted to the car body at the top; and interposed between the tops of said brackets and collars 14 on the rods 9, are cushioning springs 15. The tension of these cushioning springs 15 is regulatable by means of nuts 16 which engage screw threads at the upper ends of the hanger rods 9.

As a means to yieldingly connect the diaphragm plate 8 to the car end 7 at the top, I have shown a multi-leaf spring 17 which is secured centrally of the upper cross portion or head 18 of said face plate by a suitable clamp means 19 and which has its ends engaging brackets 20 secured to the car body as shown in Fig. I.

At the bottom, the diaphragm plate 8 is fitted, after customary practice, with a pair of transversely spaced buffer stems 21. However, instead of being of composite construction and confined to endwise movement in fixed guides as ordinarily, in accordance with my invention these buffer stems 21 are made in one piece and accorded free play to a very considerable extent secured to the car body as shown in Fig. 1.

35 accorded free play to a very considerable extent in all directions within comparatively large frontal openings 22 in hollow housings 23 into which they extend as shown in Fig. I. The housings 23 may be integral with the end sill 24 of the car as illustrated, or they may be separately constructed and fixedly secured to the sill if found more convenient or desirable in practice. As instanced in Fig. I, the buffer stems 21 are respectively formed with terminal heads 25 for the abutment of helical buffer springs 26, 40 which, at their other ends engage within conformative hollows of brackets 27 fixedly secured to the car body somewhat inward of the sill 24. The extent of expansion of the springs 26 and the outward thrust of the buffer stems 21 is limited by flexible elements in the form of chains 28. Each such chain 28 has one of its ends connected by a cross pin 29 to a clevisled stud rivet 30 secured in the abutment head 25 of the corresponding buffer stem 21, and its other end 35

connected, likewise by a cross pin 31, to a clevised bolt 32 engaged in the corresponding abutment bracket 27.

By virtue of the aforescribed construction, 5 the diaphragm face plate 8 is supported with capacity to move in and out, up or down or angularly in any direction from the normal position illustrated, the springs 15, 17 and 26 yielding individually or collectively as required to accommodate such action, while the weight of the plate is sustained solely by the hanger rods 9. Accordingly, in a train, the contacting diaphragm face plates 8 of the vestibules of contiguous car ends can adjust themselves mutually 15 with avoidance of relative motion between them notwithstanding contrary swaying or pitching of said contiguous car ends during straight away travel of the train, or by reason of angular deviations of the cars incident to rounding of track 20 curves. Under normal conditions of operation, the action of my improved vestibule construction is substantially noiseless, since frictional grating between contacting surfaces of the face plates of contiguous vestibules cannot occur, and moreover 25 since looseness at the connections between the parts is at all times absorbed by the several springs 15, 17 and 26.

Having thus described my invention, I claim:

1. In car vestibule diaphragm construction, 30 means for supporting the face plate of the diaphragm with capacity for universal movement relative to the car end; and means to yieldingly resist such movement of the face plate, including a transversely positioned multi-leaf spring 35 centrally secured to the upper or head portion of the face plate with its ends pivotally connected to the car body at the top, and a multiplicity of laterally spaced helical buffer springs interposed between the lower portion of the face 40 plate and fixed anchorages on the car body, said springs being free to flex sidewise.

2. In car vestibule diaphragm construction, 45 means for supporting the face plate of the diaphragm with capacity for universal movement relative to the car end; and means to yieldingly resist such movement, including a transversely positioned leaf spring centrally secured to the upper or head portion of the face plate with its 50 ends pivotally connected to the car body, buffer stems secured in laterally spaced relation to the lower portion of the face plate and reaching inward therefrom, compression springs interposed between the inner ends of the buffer stems and fixed anchorages on the car body; and flexible 55 means connecting the buffer stems with the anchorages to limit the outward movement of the face plate.

3. In car vestibule diaphragm construction, 60 means for supporting the face plate of the diaphragm with capacity for universal movement relative to the car end; and means to yieldingly resist such movement of the face plate including a transversely positioned multi-leaf spring centrally secured to the upper or head portion of the 65 face plate with its ends pivotally connected to the car at the top, laterally spaced buffer stems secured to the bottom portion of the face plate and reaching rearwardly therefrom, helical buffer springs interposed between the inner ends of the 70 buffer stems and fixed anchorages on the car body, and flexible chain connectors within the springs and having their opposite ends secured respectively to the buffer stems and said fixed anchorages to limit the outward movement of the 75 face plate.

4. In car vestibule diaphragm construction, 5 means for supporting the face plate of the diaphragm with capacity for universal movement relative to the car end, including a pair of hanger rods with their lower ends pivotally connected to the bottom portion of the face plate and their upper ends slidingly engaging apertured brackets secured to the car body at the top, and cushioning springs interposed between the tops of the brackets and collars at the upper ends of said 10 rods; and means to yieldingly resist such movement of the face plate including a transverse multi-leaf spring centrally secured to the upper or head portion of the face plate with its ends pivotally connected to the car at the top, a pair 15 of laterally-spaced buffer stems secured to the bottom portion of the face plate and reaching inwardly therefrom, helical buffer springs interposed between the inner ends of the buffer stems and fixed anchorages on the car body, and means 20 to limit the expansive movement of the last mentioned buffer springs.

5. In car vestibule diaphragm construction, a 25 face plate; yielding means connecting the face plate to the car body with capacity for in and out, angular and lateral movement relative to the car body; and pivot means by which the weight of the face plate is supported from the car body.

6. In car vestibule diaphragm construction, a 30 face plate; yielding means connecting the face plate to the car body with capacity for in and out, angular and lateral movement relative to the car body; and pivot means by which the weight of the face plate at opposite sides thereof 35 is supported from the car body.

7. In car vestibule diaphragm construction, a 40 face plate; yielding means connecting the face plate centrally of its top and at laterally spaced points at the bottom to the car body with capacity for universal movement relative to the latter; and pivot means by which the weight of the face plate at the sides thereof is supported from the car body.

8. In car vestibule construction, a rectangular 45 face plate; yielding means connecting the face plate centrally of its top and at its lower corners to the car body with capacity for universal movement relative to the latter; and pivot means by which the weight of the face plate at opposite 50 sides thereof is supported from the car body.

9. In car vestibule diaphragm construction, a 55 face plate; yielding means connecting the face plate to the car body with capacity for in and out, angular and lateral movement relative to the car body; and means for carrying the weight of the face plate at opposite sides thereof in the form of suspension rods having loose connections at their upper ends with the car body and pivotal connections at their lower ends with the bottom 60 of the face plate.

10. In car vestibule diaphragm construction, a 65 face plate; yielding means connecting the face plate to the car body with capacity for in and out, angular and lateral movement relative to the latter; and means for carrying the weight of the face plate at opposite sides thereof including rods loose at their upper ends in apertured brackets secured to the car body and pivotally connected to the bottom of the face plate at their 70 lower ends; and springs interposed between heads on the rods and the tops of the brackets.

11. In car vestibule diaphragm construction, a 75 face plate connected centrally at its top by a compressible spring to the top of the car end;

5 pivoted means for yieldingly supporting the face plate with capacity to swing sidewise about the central top connection aforesaid; and laterally flexible compressible spring means connecting the lower corners of the face plate to the lower portion of the car end.

12. In car vestibule diaphragm construction, a compressible spring connecting the face plate

centrally of its top to the top of the car end; laterally yielding means connecting the bottom corners of the face plate with the bottom of the car end; and pivotally connected yielding hangers by which the weight of the face plate at opposite sides thereof is supported from the car body. 5

HARRY L. DECKER.
